CLAIM

The ornamental design for a filter element, as shown and described.

DESCRIPTION

FIG. 1 is a front, left, and bottom perspective view of a filter element, showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is an enlarged bottom view thereof.

The broken lines depict portions of the filter element that form no part of the claimed design.
